Thomas Cunningham of Pittsburg Penn
Sells Patent

The like is referred to in these Sales Patent and making part of the same, containing a description in the words of the said Thomas Cunningham him self of his improvement, being a machine called the "Pittsburg Floating Dock":

To all persons to whom these presents shall come, I Thomas Cunningham of the City of Pittsburg, County of Allegheny and State of Pennsylvania, ship Carpenter and Fitter. Have invented constructed made and applied to use, a new and useful improvement discovery and machine called the Pittsburg Floating Dock. The following Specification shewz the manner of construction, its use, and the application of its machinery for building or repairing Ships, Steam Boats, and any other a safe fit for Navigable purposes viz. The Pittsburg Floating Dock is in the form of a square vessel made of wood 140 feet long, 34 feet wide at bottom, 36 feet wide at the top and 10 feet deep, but which size may be varied according to the size of vessels which it is intended should be either built or repaired therein. The bottom is constructed of 3 tiers of timbers. The first is lower set running longitudinally, spaced off at about 15 feet apart so as to insure the breadth of bottom, over these are only or lateral beams at the distance of 6 feet apart bolted down on the lower timbers and well tied fastness to the sides of the vessel. On these of lateral frame or floor, the vessel to be built or repaired must be blocked ^{and} raised up at a proper height to allow her growing to be done with ease to the workman.

The ends of the vessel are framed together with king posts, braces and sides and secured to the sides by strong knees. The sides are composed of a number of uprights about 3 feet apart framed into the lower longitudinal beams, and secured at top and bottom of and the bottom by strong wall pieces, which go round the dock. The bottom is covered with 4 and one half inch and the sides with 3 inch plank, on one end a gate is formed to open and shut at an elevation of about 10 feet above the bottom, and made of sufficient width to admit in or out of the dock.

such vessels as may have occasion to use it. It is hung on its lower margin at edge by large strap hangers and joints so made under light by means of leather and braded points and is raised or let fall by means of ropes with tackle and pulleys. The 2 pumps are concealed on the end opposite to that where the gate is placed, and scuttle holes are provided in each angle of the dock. To use this graving dock it must be sunk in whatever water it is needed. The gate must be thrown open and the vessel to be repaired warped into her. The gate is then closed, the pump geared to the steam engine, and in a short time she will be dry on side and again afloat with the vessel to be repaired braced upon her stocks. After building or repairing is completed the scuttle holes are opened and the floating Graving Dock sunk. The gate thrown open and the vessel built or repaired floats off and immediately after another vessel is warped in for repair and the foregoing operation goes on in regular succession as business may require.
